UNITED STATES PATENT OFFICE

2,436,075

DISPENSING PILLBOX

Charles Orban, Detroit, Mich.

Application July 27, 1945, Serial No. 607,312

4 Claims. (Cl. 312—47)

1

My invention relates to containers and has for an object to provide a box for pills, tablets, pellets or other articles having means whereby a single one of the contents of the box may be dispensed at a time.

Another object of the invention is to provide a dispensing box having a plurality of separate compartments therein and means whereby a pill or the like may be dispensed from first one and then another of the compartments.

A further object of this invention is to provide in a container a slideable dispenser connected therewith adapted to deliver from different compartments in the box.

Other features and advantages will become more readily apparent from the following description and the accompanying illustrative drawings in which:

Figure 1 is a perspective view of my dispensing pill box,

Figure 2 is a vertical sectional view thereof,

Figure 3 is a sectional view taken on line 3—3 of Figure 2,

Figure 4 is a detail perspective view of a dispensing member, and

Figure 5 is a section on line 5—5 of Figure 1.

In the accompanying drawings as above enumerated and in the following specification, like characters of reference indicate like parts throughout. The numeral 10 indicates my improved pill box which consists of a block 11 or receptacle, which may be of wood, plastic, or any other suitable material, and which is provided with bores or compartments 12 and 13 extending entirely through the block and the upper ends 14 and 15, of which are flared out for easy filling of the bores with pills 16, tablets, lozenges, etc.

The lower end 17 of the block is provided on each side 18 and 19 with parallel grooves 20 and 21 forming a trackway for the inturned flanges 22 and 23 of a reciprocating slide member or slider valve 24. The bottom wall 25 of this slider valve is extended at both ends and turned up to form end walls 26 and 27 and then returned upon itself to operate in slots 28 and 29 in the lower part of the end walls 30 and 31 and form alternate walls or closures 32 and 33 for the breeches 34 and 35 of the bores 12 and 13.

The closure members 32 and 33 are each spaced high enough above the wall 25 to form pockets 36 and 37 of a depth to freely admit one pill at a time to enter therewith and each pocket is provided with an outlet aperture 38 and 39 respectively. The wall 25 is turned up at right angles on each side to form the side walls 40

2

and 41 from which said flanges 22 and 23 project inward and into the respective longitudinal slots 20 and 21. Slidably seated upon the top 42 of block 11 is a closure 43 for the said bores 12 and 13.

To operate the device is extremely simple, it being only necessary to slide the valve 24 from one end of the block to the other end whereupon a pill will be dropped into the hand of the user and upon reversing the valve another pill will be dropped. For instance, when the valve is in the position shown in Figure 2 of the drawings, a pill has just been dropped through the aperture 38 and the closure member 33 has been moved from under breech 35, permitting pill 44 to drop into pocket 37, where it is held by the very slightly turned down free edge 45 of member 33 until another pill is wanted. When end 27 is pushed to the right as far as it will go, thus moving aperture 38 out of the path of breech 34, moving closure 33 in and between pills 44 and 46, and bringing aperture 39 under pill 44, said pill is permitted to drop therethrough and into the hand of the user. At the same time closure 32 moves from under pill 47 in bore 12 allowing it to drop into pocket 36 where it will be held by the slightly curved down edge 48.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to in actual practice, if desired.

Having now described my invention that which I claim as new and desire to procure by Letters Patent is:

1. A dispensing device comprising a receptacle having a plurality of compartments therein, partition means for separating said compartments, grooves in said receptacle, means slidably received in said grooves for dispensing successively from a first of said compartments and a second of said compartments, thence from the first compartment, said dispensing means comprising a slider valve having a recess therein, walls partially covering said recess, each wall slidably under a predetermined compartment, spaced apertures in said valve, said recess communicating with successive compartments upon actuation of said valve.

2. A dispensing device comprising a receptacle

having a plurality of compartments therein, means for separating said compartments and for guiding pills to a predetermined position, said receptacle being provided with longitudinal grooves, means slidably received in said grooves for dispensing alternately from said compartments, said separating means including a partition extending below said grooves, said dispensing means comprising a slider valve having a recess and base therein, spaced apertures in said base, said recess communicating with alternate compartments upon actuation of said valve, said partition extending within said recess for engaging pills to retain them in position until said apertures come beneath the pills, upon actuation of said valve.

3. The combination of claim 1, wherein said partition means is engageable with alternate opposite edges of said walls for limiting the travel of said valve.

4. In a dispensing device, a block having two parallel bores adapted to receive pills therein, a slider valve slidably connected with said block and beneath the same, said slider valve having a base, two side walls, two end walls, and top wall sections extending toward each other leaving a space therebetween, two openings in said base, one beneath each top wall section, said bores

being separated by a partition having a portion extending into the said valve in the space between the top wall section, there being sufficient clearance between the partition and the edges of said wall section to permit the valve to be moved at will in a portion of the space between the walls beneath a bore, said partition holding a pill which had dropped into the valve against lateral movement as the valve is actuated so that an opening 10 in the base of said valve will register with the pill to enable it to drop therefrom.
